UNITED STATES PATENT OFFICE.

CHARLES E. GODLEY, OF DETROIT, MICHIGAN, ASSIGNOR, BY MESNE ASSIGNMENTS,
TO EDMUNDS & JONES CORPORATION, OF NEW YORK, N. Y., A CORPORATION OF
NEW YORK.

PLUG.

1,190,750.

Specification of Letters Patent.

Patented July 11, 1916.

Application filed June 28, 1913. Serial No. 776,261.

To all whom it may concern:

Be it known that I, CHARLES E. GODLEY, a citizen of the United States of America, residing at Detroit, in the county of Wayne 5 and State of Michigan, have invented certain new and useful Improvements in Plugs, of which the following is a specification, reference being had therein to the accompanying drawings.

10 My invention relates to plugs for lamp sockets and resides in the provision of a simple and efficient plug, and in certain constructions, arrangements and combinations of parts as will more fully hereinafter appear and as claimed.

In the drawings, Figure 1 is a perspective view of a lamp socket provided with a plug embodying the invention; Fig. 2 is a longitudinal, central section therethrough; and 20 Fig. 3 is a fragmentary perspective view through the portion E.

B designates a plug comprising a casing C, preferably a metallic sleeve, and an insulating core D provided with a portion extending within and fitting one end of the sleeve C, and with another portion E arranged without the sleeve.

F is a pin for attaching the sleeve to the core.

30 I designates one of the electrical contacts and J the other. These contacts are carried by the core D and each comprises a shank K having a head L preferably integral therewith and a terminal or lead-attaching portion M having a threaded engagement with a stud N of reduced cross-section on the end of the shank. The shank K has a longitudinal sliding engagement with an aperture N' in the core D and the lead-attaching portion 35 M has a sliding engagement with an enlarged bore O arranged upon one side of and alining with the aperture N'. Upon the opposite side of the aperture is a second alined bore P of a diameter sufficiently larger than the shank so as to receive a spring Q coiled around the shank. One end of this spring bears against the head L while the other is seated upon the base R of the bore P. The spring however, tends to project the head L 45 of the contact forwardly within the lamp bulb engaging portion S of the plug. Forward movement of the contact however, is limited by the terminal-engaging portion contacting with the inner end of the bore O.

50 Communicating with the bore O is a cham-

ber T that opens out through the periphery of the portion E of the core and through which the end of the lead or wire U passes into engagement with the terminal-attaching portion M. The latter is preferably in the 60 form of a box having one end threaded to engage the threaded stud N and having its opposite end internally threaded to receive a clamping screw V, while extending through the side of the box is an aperture W for receiving the wire T. The head of the clamping screw is accessible through the end of the bore O, and the latter and the box are preferably of rectangular cross-section so as to prevent turning of the box during the clamping of the terminal in place. The lamp-engaging portion is provided with bayonet slots Y for engaging studs upon the sides of the lamp bulb, in the usual manner, the springs upon the contacts serving to hold the 75 lamp bulb in place. The contacts I and J are of course, insulated from each other and also the chambers T for receiving the wires are separated by a partition Z of insulating material, this being preferably accomplished 80 by forming the partition integral with the core D.

By the structure hereinbefore described, when it is desired to attach the wire to the contact, the end of the wire is inserted 85 through the chamber T and the aperture W into engagement with the box M and then clamped thereto by means of the screw V. When the wire is so attached there is a positive connection between the wire and the 90 head of the contact, which in effect forms a unitary structure. Therefore, but a small portion of the current will pass through the spring Q, eliminating any tendency for this spring to become overheated and crystal- 95 lized. The chamber T is sufficiently elongated to permit the end of the wire to move with the box during the travel of the shank within the aperture N' when the lamp bulb is being engaged with the socket, and in all 100 positions of longitudinal movement of the contact it will be noted that the parts of the contact and the wire or lead remain in fixed relation.

What I claim as my invention is:—

1. In a plug, the combination with a lamp-bulb engaging portion, of an insulating core operatively connected thereto and provided with an opening extending longitudinally therethrough, a contact member extending 110

- through said opening a spring sleeved upon the contact tending to yieldably retain one end of the contact within the lamp-bulb engaging portion, and a lead-attaching section 5 fixedly connected to the contact to move as a unit therewith and constituting a stop to limit displacement of the contact into the lamp-bulb-engaging portion.
2. In a plug, the combination with a sleeve 10 having a lamp bulb engaging portion, an insulating core having a section arranged within the sleeve and operatively connected thereto, said core being provided with an aperture and with alining bores upon opposite 15 sides of said aperture, a contact comprising a shank slidably engaging said aperture, a head upon one end of the shank projecting within the lamp bulb engaging portion, a spring arranged within one of the 20 bores and sleeved upon the shank, the ends of said springs respectively engaging the base of said bore and said head, and a lead-attaching section arranged within and slidably engaging the other bore, said lead-attaching section including a clamping member 25 accessible through the last-mentioned bore.
3. In a plug, the combination with a sleeve provided with a lamp bulb engaging portion, of an insulating core having a section arranged within said sleeve and provided with a portion arranged therewithout, a contact carried by said core having its forward end arranged within said lamp bulb 30 engaging portion, a spring exerting a forward pressure on said contact, as a whole, a terminal-engaging section carried by the rear end of said contact and arranged within said core, and a terminal chamber extending 35 laterally through said core in operative relation to said terminal-engaging section.
4. In a plug, the combination with a sleeve provided with a lamp bulb engaging portion, of an insulating core having a section arranged within said sleeve and provided with a portion arranged therewithout, a spring-pressed contact carried by said core having its forward end arranged within said lamp bulb engaging portion, a terminal-engaging section carried by the core and arranged therewithin, a chamber extending laterally through said core in operative relation to said terminal-engaging section, and a clamping member carried by the terminal- 50 engaging section accessible through the end of said core.
5. In a plug, the combination with a sleeve having a lamp bulb-engaging portion, of an insulating core having a portion projecting 55 into said sleeve, contact members extending through said insulating core longitudinally of the sleeve and having portions projecting into the bulb-engaging portion thereof, terminals arranged within the insulating core exterior to the sleeve, respectively connected 65 with said contact members, and clamping members accessible through the outer end of the core engaging the terminals, said end being formed with laterally opening chambers for the engagement of conductors with 70 the terminals.
6. In a plug, the combination with a member arranged to engage a lamp bulb at one extremity, of an insulating member engaged with the other extremity of the bulb-engaging member, contact members passing through the insulating member and longitudinally adjustable as a whole relative thereto, having end portions projecting into the bulb-engaging member, the insulating 75 member being formed with chambers into which the other end portions of the contact members respectively project, said chambers opening in the lateral face of the insulating member to admit lead wires. 80
7. In a plug, the combination with a sleeve having a lamp bulb engaging portion, of an insulating core having portions interior and exterior to said sleeve, said core having a longitudinal opening and having a laterally 85 opening passage in its exterior portion intersecting said longitudinal opening, a contact mounted in said longitudinal opening, a conductor entering said laterally opening passage to engage said contact, and a binding member accessible through the outer end of said core engaging said conductor with said contact. 90
8. In a plug, the combination with a sleeve provided with a lamp bulb engaging portion, of an insulating core having a section arranged within said sleeve and provided with a portion arranged therewithout, a contact carried by said core having its forward end arranged within said lamp bulb engaging portion, a spring exerting a forward pressure on said contact, a terminal engaging section carried by the end of said contact and movable therewith, said insulating core being formed with a chamber extending laterally therethrough to receive lead wires extending to said terminal engaging section, said chamber being proportioned to allow a limited freedom of motion of said lead wires during adjustment of said contact. 100
- In testimony whereof I affix my signature in presence of two witnesses.

CHARLES E. GODLEY.
